(57) **CLAIM**

The ornamental design for a modular public space structure, as shown and described.

DESCRIPTION

FIG. 1 is a front perspective view of the modular public space structure;

FIG. 2 is a front elevational view thereof, the rear elevational view, the right side elevational view and the left side elevational view being a mirror image;

FIG. 3 is a top plan view thereof;

FIG. 4 is a bottom plan view thereof; and,

FIG. 5 is an exploded front perspective view thereof, the broken lines are for purposes of illustration and form no part of the claimed design.

The surface shading lines shown in the drawings are provided only to indicate the character and/or any contour or curvature of the surfaces of the design. They do not indicate color, texture, markings that actually exist thereon, indicia, graphic representations, surface treatment, or any other ornamentation applied to the article, and form no part of the claimed design.
